[57] CLAIM

The ornamental design for a moisture sensing alarm for a diaper, as shown and described.

DESCRIPTION

FIG. 1 is an enlarged perspective view of a moisture sensing alarm for a diaper showing my new design;
FIG. 2 is a side elevational view thereof, with the undis-
closed sides being a mirror image;
FIG. 3 is a top plan view thereof; and,
FIG. 4 is a bottom plan view thereof.
